BOWLING PIN TREATMENT APPARATUS
 Norbert A. Schad, 239 Chestnut St., North Syracuse, N.Y.
 Filed Aug. 19, 1963, Ser. No. 302,901
 3 Claims. (Cl. 118—501)

This invention relates to apparatus for the treatment of bowling pins, and more particularly to a rack for accommodating bowling pins in the operation of dipping the pins as in clear lacquer, to extend the pin life.

In the operation of bowling alleys it is desirable from time to time to treat the pins by partial or substantially complete immersion in a treatment solution such as a clear lacquer to extend the life of the pins. Such treatment renders such pins reusable, fills incipient cracks, and protects the original decorative finish of the pins. The treatment of pins, by dipping has been a cumbersome operation.

The present invention is directed to apparatus adapted to render the dipping of a set or sets of bowling pins a relative easy operation, whereby one or more sets of pins may be quickly treated, without wastage of lacquer. The invention is further adapted for use in the partial dipping as for example only the pin heads, as well as the entire pin. The apparatus may be folded for convenient storage when not in use.

The above and other novel features of the invention will appear more fully hereinafter from the following detailed description when taken in conjunction with the accompanying drawings. It is expressly understood that the drawings are employed for purposes of illustration only and are not designed as a definition of the limits of the invention, reference being had for this purpose to the appended claim.

In the drawings, wherein like reference characters indicate like parts:

FIGURE 1 is a front elevational view of the apparatus, in position for full pin treatment;

FIGURE 2 is an end elevational view of the apparatus, as shown in FIGURE 1;

FIGURE 3 is a front elevational view of the apparatus in position for pin tip treatment;

FIGURE 4 is a sectional view of the underside of the support deck, taken on the line 4—4 of FIGURE 1;

FIGURE 5 is a sectional view taken on the line 5—5 of FIGURE 1;

FIGURE 6 is a sectional view taken on the line 6—6 of FIGURE 5;

FIGURE 7 is an enlarged fragmentary view of the leg positioning apparatus and pan support; and

FIGURE 8 is an enlarged fragmentary view with parts in section of a pin hanger.

Referring to FIGURES 1 and 2, there is shown a support deck or plate 20, mounted on tubular legs 22, 24, 26 and 28, the upper ends of which are rigidly set in transverse members 30 and 32. Each leg, comprises telescopic tubes 34 and 36. The inner tube 34 is adapted to be supported at a selected height on the upper end 38 of the outer tube 36 by a removable key 40, which extends through apertures 35 in the tube 34, the apertures being so located so as to hold the deck 20 at a suitably elevated height.

The underside of the deck 20 is provided hanging support means, such as hooks 41, at suitable spacings whereby a plurality of pins, such as 42 may be hung therefrom in inverted position. For this purpose as indicated in FIGURE 8, each pin may have a spring hanger 48 inserted in an aperture 44 extending inwardly from the base of the pin 46. The spring hanger 48 has a loop 50 for engagement with one of the hooks 41, and is provided with oppositely projecting teeth 52 for en-

gagement in the aperture 44. The hanger may have its teeth 52 sprung together to release the same from the pin for removal therefrom.

As shown in FIGURE 3, the keys 40 are removed, and the upper leg sections 34 are telescoped into the lower leg section 36 to lower the height of the deck 20. The deck is provided with key shaped notches 60, adapted to receive the neck of a pin to hold the same in inverted position as indicated in FIGURE 3, five such notches being preferably spaced uniformly along the opposite sides of the deck.

Below the deck 20 is a drip pan 70 having inclined faces 72 and 74 and discharge spouts 76 and 78. The pan has a surrounding flange 80 and the inclined faces 72 and 74 meet along a central ridge line 82. The sides of the pan incline outwardly and downwardly toward the discharge spouts 76 and 78 as indicated at 84 and 85. Beneath the pan, in brackets 86 secured to the bottom, are spaced support rods 88 and 90, which terminate in depending hooks 92, adapted to engage in loops or eyes 94 affixed to the lower leg sections 36. The rods and hooks tend to brace the four legs, when the pan is in place, as indicated in FIGURES 1-3, 5 and 7, and assist in rigidifying the pan. The rods may be welded or otherwise rigidly affixed to the brackets as indicated at 87.

The spouts 76 and 78 are of such a height as to drain into dip tanks, 96 and 98 which may be cylindrical, and of a height of about 20", the height and diameter of such tanks being adequate to hold a quantity of treating solution of a depth to permit substantially complete immersion of a pin therein.

Each of the keys 40 may be provided with a short flexible chain 41, the ends of which are attached to the respective lower leg sections 36, and the transverse members 30 and 32 may be hinged to the underside of the deck 20, as at 31 and 33 whereby the legs may be folded, after removal of the pan, for convenient storage.

It will be seen that if it is desired to dip the pins in their entirety, each pin is quickly provided with a hanger 48, the pin dipped in one or the other of the dip tanks 96 and 98 to a depth approaching the pin base, after which the pin is hung upon one of the hooks 41, it being understood that for full treatment, the deck will be elevated as shown in FIGURES 1 and 2. As fast as a pin is dipped it is hung over the pan to drip dry, and subsequent pins are treated and hung. In about the time 20 pins are dipped, the original pin will be found to have dripped dry, and therefore be ready for removal from its hook.

When it is desired to treat only the pin tips, the rack is lowered to the height indicated in FIGURE 3. As each pin is dipped to treat the same up to the decorative neck band indicated, it is inserted in one of the key shaped slots 60, for draining and drying. Since drainage is much quicker for pins only partially dipped, the provision of ten slots 60 will suffice, since in the time ten pins are partially dipped the first pins dipped may be removed and provide space for succeeding sets of pins. The pan collects the excess lacquer returning the same to the dip tanks, so as to conserve lacquer. It will be understood that such lacquer is highly inflammable, and that the apparatus enables the dipping operation to be carried on without spillage, or mess, since as each pin is dipped and placed in position to dry, it may at all times be retained over the pan so that all dripping is collected and returned to the dip tanks.

The lowering of the deck, for partial dipping reduces the height to which each pin must be lifted after dipping, and reduces the height of fall of the drip from the treated pins. This reduces the evaporation of the treatment liquid, reduces the accompanying odor. Thus the

provision of a support deck, which holds the pins for dripping close to the pan so that flow back to the tanks is expedited, save liquid, reduces fire hazard, and also minimizes the presence of vapor in the air in the immediate region of the apparatus, whereby the operation of treating the pins becomes less offensive.

While a single form of the invention has been referred to, it will be understood that the invention is not limited thereto. As various changes in the construction and arrangement may be made without departing from the spirit of the invention, as will be apparent to those skilled in the art, reference will be had to the appended claims for a definition of the limits of the invention.

What is claimed is:

1. A bowling pin treatment apparatus comprising a rectangular horizontal top deck, said deck having a plurality of uniformly spaced keyhole shaped notches in the longitudinal side edges thereof to engage the stems of inverted bowling pins, and a plurality of hooks depending from the underside thereof for suspending inverted bowling pins therefrom, transverse members secured to the deck along the underside of the end edges thereof, a leg secured to and extending downward from each of the opposite ends of said members, each of said legs comprising a lower tubular member and an upper tubular member telescopically disposed within the lower member, a substantially rectangular pan disposed beneath said deck and having opposed surfaces inclining downwardly from the longitudinal center thereof detachably secured to the upper portions of each of the lower leg members, said pan having a marginal upstanding flange, and opposite side edges inclining outwardly and downwardly toward the center of the sides thereof and terminating in drain spouts disposed centrally on opposite sides of the pan, the lower members of said legs being of a length to engage said transverse members, and support the deck at a height above said pan sufficient to accommodate inverted bowling pins in said slots, upon the upper tubular member being fully telescoped within the lower tubular member and the upper members of said legs being adapted to be extended to support said deck at a higher level, and removable key means adapted to be projected through transverse apertures in said upper leg members to engage the ends of the lower members to hold said leg members in an extended position, whereby to support said deck above said pan at a height sufficient to accommodate inverted bowling pins suspended from said hooks, and a dip tank for holding bowling pin treatment solution disposed beneath each spout.

2. A bowling pin treatment apparatus comprising a

5 rectangular top deck, said deck having a plurality of uniformly spaced keyhole shaped slots in the longitudinal side edges thereof to engage the stems of inverted bowling pins, and a plurality of hooks depending from the underside thereof for suspending inverted bowling pins therefrom, leg means for supporting said deck, a substantially rectangular pan disposed beneath said deck and having opposed surfaces inclining downwardly from the longitudinal center thereof and supported by said leg means intermediate their length, said pan having a marginal upstanding flange, and opposite side edges inclining outwardly and downwardly toward the center of the sides thereof, and terminating in drain spouts disposed centrally on opposite sides of the pan, said leg means including means for supporting said deck at either of two levels above said pan, whereby to support said deck above said pan at a height sufficient to accommodate inverted bowling pins suspended from said hooks, and at a height sufficient to accommodate inverted bowling pins having their stems disposed in said slots.

10 3. A bowling pin treatment apparatus comprising a rectangular top deck, said deck having a plurality of uniformly spaced keyhole shaped slots in the longitudinal side edges thereof to engage the stems of inverted bowling pins, and a plurality of hooks depending from the underside thereof for suspending inverted bowling pins therefrom, leg means for supporting said deck, a substantially rectangular pan disposed beneath said deck and having opposed surfaces inclining downwardly from the longitudinal center thereof, said pan having a marginal upstanding flange, and opposite side edges inclining outwardly toward the center of the sides thereof, and terminating in drain spouts disposed centrally on opposite sides of the pan, said pan having two support rods secured 15 to the underside of said pan adjacent the side edges thereof, said support rods having downwardly bent ends projecting into eyes affixed to said leg means.
